CLAIM

The ornamental design for a spout, as shown and described.

DESCRIPTION

Spout

1. Wall-mounted spout

2. Tap spout

FIG. 1.1 is a perspective view of a spout, showing our new design;

FIG. 1.2 is front elevation view thereof;

FIG. 1.3 is a top plan view thereof;

FIG. 1.4 is a side elevation view thereof;

FIG. 1.5 is a bottom side plan view thereof;

FIG. 1.6 is another side elevation view thereof; and

FIG. 1.7 is an enlarged view taken from 1.5;

FIG. 2.1 is a perspective view of a spout, showing our new design;

FIG. 2.2 is front elevation view thereof;

FIG. 2.3 is a top plan view thereof;

FIG. 2.4 is a side elevation view thereof;

FIG. 2.5 is a bottom side plan view thereof;

FIG. 2.6 is another side elevation view thereof; and

FIG. 2.7 is an enlarged view taken from 1.5.
